United States Patent Office

Des. 203,012

Patented Nov. 23, 1965

203,012

MACHINE FOR APPLYING PRINTED ADDRESSES TO MOVING ARTICLES

Dana W. Mox, Glenview, Ill., assignor to Cheshire Incorporated, a corporation of Illinois

Filed July 31, 1964, Ser. No. 81,106

Term of patent 14 years

(Cl. D64—11)

FIG. 1

FIG. 2

FIG. 3

FIG. 4

FIG. 1 is a front perspective view of a machine for applying printed addresses to moving articles, showing my new design.

FIG. 2 is a front elevational view thereof.

FIG. 3 is a rear perspective view thereof; and

FIG. 4 is an end view thereof.

I claim:

The ornamental design for a machine for applying printed addresses to moving articles.
